UNITED STATES PATENT OFFICE.

ALBERT LOUIS BOUCHER, OF ASNIÈRES, FRANCE, ASSIGNOR OF ONE-HALF TO CHARLES COMIOT, OF PARIS, FRANCE.

APPARATUS FOR GAS HEATING STOVES AND RADIATORS.

984,743.

Specification of Letters Patent. Patented Feb. 21, 1911.

Application filed May 14, 1909. Serial No. 495,922.

To all whom it may concern:

Be it known that I, ALBERT LOUIS BOUCHER, a citizen of the Republic of France, residing at Asnières, in France, have invented certain new and useful Improvements in Apparatus for Gas Heating Stoves and Radiators, of which the following is a specification.

This invention relates to gas heating stoves, radiators and the like of the type wherein no discharge shaft is employed.

Gas heating stoves provided with a discharge shaft for the products of combustion obviously do not give out any injurious or offensive gases, but as the loss of heat carried away by the partially consumed products of combustion is large, the consumption of gas for producing a given temperature is very high, and the efficiency of the apparatus correspondingly low. Gas heating apparatus without a discharge shaft, though more efficient, give off a quantity of offensive gases and are not so safe on this account.

According to this invention a gas heating apparatus is provided in which the products of combustion, instead of escaping directly into the atmosphere or through a discharge shaft circulate in the apparatus itself, heating the walls of the casing, and returning to the burners passing through the flame and the radiating members where complete combustion takes place, the radiating members comprising removable and interchangeable metallic elements arranged above the burners. This arrangement has the following advantages: Great economy, owing to the complete combustion of the initially, partially consumed gases, and to the recovery of the heat ordinarily carried away by them; absence of dangerous and unpleasant gases and the production of a high temperature with a small consumption of gas, for owing to the flames being in contact with divided incandescent metal members, the gases are burned in a more complete manner than in apparatus where the incandescent members are of fire proof material.

In the accompanying drawings Figure 1 is a perspective view of a complete gas heated radiator according to this invention, some of the metallic radiating members being removed and a portion of the front wall

being broken away to show the burner. Fig. 2 is a diagrammatic cross-section showing the path of the gases through the apparatus. Fig. 3 is a plan of a blank for a radiating member of slightly different form than that shown in Figs. 1 and 2. Fig. 4 is a perspective view of the blank after its flanges have been formed. Fig. 5 is a section of the gas admission valve. Fig. 6 is a partial view of a plurality of radiating members of the form produced by blanks such as illustrated in Figs. 3 and 4, one element being shown as partially inserted. Fig. 7 is a cross-section of the radiating members, shown in Fig. 6, one of the elements being shown in the operative position. Fig. 8 shows a perforated blank intended to form the radiating element shown in Figs. 1 and 2. Fig. 9 is a perspective of the blank shown in Fig. 8 bent so as to constitute the element in question. Fig. 10 is a view of the whole of the radiating plate, a metallic element being also shown in the course of being erected.

The body of the apparatus comprises a double casing formed of two end plates *a* to which are connected side walls comprising two metal sheets *b*, *b'*, between which is left an annular circulating chamber. The front portion of the walls *b*, *b'* is cut away to form two rectangular openings, the front one of which constitutes the mouth of the radiator. The rear opening is closed by removable cast iron plate *c* which engages projections of the end plates *a* and is provided with nickel plates or flanges *d* riveted thereto and adapted to serve as vertical guides for removable and interchangeable metallic radiating members *e* mounted above the burners *g* of the supply pipe *f* which is arranged in the front lower portion of the radiator.

The various parts constituting the apparatus are held together by means of ties comprising bolts passing through the whole length of the apparatus, and provided with tightening nuts *h* which in the case of the lower bolts bear against plates *i* provided with extensions forming legs for the apparatus while the upper bolts engage plates *j*.

The pipe *f* in which are formed the burners is connected to one of the plates *a* by

means of a washer *k* and of a screw *k'* secured in the plug closing the end of the tube.

As shown by the arrows (Fig. 2) the hot gases pass through the hollow body of the casing and, after having heated it, return and meet the flames of the burner, which brings about a complete combustion and prevents any offensive smell, the surrounding air passing through the radiator and becoming heated thereby and by flowing through the inner space *l* between the outer walls of the sheet *b*.

The detachable radiating elements *e* shown in Figs. 3, 4, 6 and 7 are designed in the following manner:—In the center and at the edge of a metal blank about 0.3 mm. thick (preferably of nickel) a slot *m* is formed (Fig. 3) enabling the two parts *n* and *o* thus separated, to be bent at right angles and in the opposite directions to each other. The flat portion is subsequently cut out to form fins or a comb along its free edge, and the teeth thus formed, which become incandescent by contact with the burner flame, are bent outward away from each other as shown in Fig. 7.

The radiating fins *e* are mounted in guides formed by the nickel flanges *d* riveted side by side on the plate *c*. The flanges *d* are provided with a central longitudinal rib which the heads of the rivets engage.

In the construction shown in Figs. 1, 2 and 8-10, the removable and interchangeable radiating members *e* comprise conical sleeves which surround their respective burners. These sleeves are provided with transverse slots through which the air for combustion is admitted and a draft chimney is thus formed into which is drawn in and burned all the gases from the burners direct, and the incompletely burned gases which have flowed through the casing of the apparatus, complete combustion of all the gases being thus effected and the maximum use made of the heat so produced. Moreover, these sleeves are less fragile than the radiating fins last described. In this modified construction, the radiating fins comprise a metal blank *r* of the shape shown in Fig. 8, in which are stamped out grooves *s* symmetrical relatively to the longitudinal axis of the blank and arranged concentrically with its curved base. The blank is then bent and folded along a generatrix, so as to form a truncated cone, whereupon the superimposed, parallel edges of the blank are bent back (as shown in Fig. 9) so as to form two projections *n o* in the same plane and at right angles to the plane portions of the chimney. The radiating members thus constructed are mounted in the guides *d* on the radiating plate *c* as shown in Fig. 1.

In the Bunsen burner which is screwed to the end of the burner tube *f*, the supply

of gas from the valve is controlled by a pointed rod *p*, which enables the valve to be of circular shape. The result is that it is possible to modify the supply of the gas without changing its pressure, as is the case with valves provided with a transverse screw. A sleeve *q* can be adjusted on the pipe to regulate the air supply in the known manner.

What I claim as my invention and desire to protect by Letters Patent is:—

1. In a gas heating stove of the kind which operates without a chimney, the combination of a double casing constituting an annular chamber, a burner in said chamber, the casing having an opening in its outer wall, and a removable radiating member within the casing adjacent to the opening and disposed above the burner comprising a sheet metal truncated cone having at its rear oppositely extending lateral projections which engage a member of the casing as set forth.

2. In a gas heating stove of the kind which operates without a chimney the combination of a double casing constituting an annular chamber, a burner in said chamber, the casing having an opening in its outer wall, and a plurality of removable radiating members, within the casing adjacent to the opening, disposed above the burner and each comprising a sheet metal truncated cone provided at its rear with means engaging a wall of the casing as set forth.

3. In a gas heating stove of the kind which operates without a chimney the combination of a double casing constituting an annular chamber, a burner in said chamber, the casing having an opening in its outer wall and a coincident opening in its inner wall, a removable plate closing the opening in the inner wall, and metallic radiating members, removably mounted within the casing above the burner and each comprising an interchangeable sheet metal truncated cone having at its rear means detachably engaging said plate as set forth.

4. In a gas heating stove of the kind which operates without a chimney the combination of a double casing constituting an annular chamber, a burner in said chamber having a plurality of jets and extending along the lower part of said chamber, the casing having an opening in its outer wall and a coincident opening in its inner wall, a removable plate closing the opening in the inner wall, vertical guides formed on said plate and a plurality of interchangeable radiating members, each comprising a sheet metal truncated cone, adapted to be removably inserted in the guides above the burner jets as set forth.

5. In a gas heating stove of the character described, the combination of a suitable cas-

ing having an opening in its front wall, a plurality of plates attached to the casing wall opposite said opening and forming with said wall guide ways, radiating members each having at its rear means detachably engaging one of said guide ways, and a burner below the radiating members.

In testimony whereof I have signed my name to this specification in the presence of two subscribing witnesses.

ALBERT LOUIS BOUCHER.
